UNITED STATES PATENT OFFICE

HENRY G. VENABLE AND GEORGIA N. VENABLE, OF TAMPICO, MEXICO

LIQUID ABSORBING PAD

Application filed October 19, 1929. Serial No. 400,990.

This invention relates to liquid absorbing pads, and an object of the invention is to provide a pad for placing on supporting surfaces under glasses, pitchers and other receptacles whereby the condensation which forms and accumulates on the outside of the receptacles when used for serving cold beverages may be absorbed and prevented from wetting the supporting surfaces.

Another object of the invention is to provide means on the upper side of the pad so that it may be attached to the bottom of a receptacle.

Further objects of the invention are to provide, in a manner as hereinafter set forth, a device of the character referred to, that is strong, compact and durable, thoroughly reliable for its intended purpose, very simple in its method of assembly, and comparatively inexpensive to manufacture.

With the foregoing and other objects in view, the invention consists of a novel combination, construction and arrangement of parts as will be hereinafter more specifically described and illustrated in the accompanying drawing, wherein are disclosed embodiments of the invention, but it is to be understood that changes, variations and modifications may be resorted to without departing from the spirit of the claims hereto appended.

In the drawing, wherein like reference characters denote like parts throughout the several views:

Figure 1 is a top plan view of the one form of the invention.

Figure 2 is a transverse section taken substantially on line 2-2 of Figure 1.

Figure 3 is a transverse sectional view showing a modified form of the invention.

Figure 4 is a transverse sectional view showing another modification of the invention, and

Figure 5 is a top plan view of the modified form shown in Figure 4 of the drawing.

The invention in its broadest aspect, contemplates the use of two sheets of material disposed in spaced relation to each other, with a layer of loose, fibrous, liquid absorbing material disposed therebetween. The

layer and the sheets are to be coupled together so as to form a composite pad. The underlying sheet may be processed to make it liquid proof. If desired, means may be provided for attaching the composite pad to articles of tableware.

Referring to the drawing in detail, and particularly to Figures 1 and 2 thereof, 6 indicates the overlying sheet and 7 indicates the underlying sheet. The sheets are disposed in spaced relation to each other and as shown are circular in form, although it is within scope of the invention to make them of any desired shape.

The sheets 6 and 7 may be formed of paper. The sheet 6 may be perforated as indicated at 8 to within a short distance of the edge thereof. Between the sheets 6, 7, there is disposed a layer 9 of loose, compressible, fibrous, liquid absorbing material. The layer 9 may be composed of loose vegetable fibers such as cotton, loose animal fibers such as wool, or any other loose, fibrous, compressible liquid absorbing material capable of absorbing an appreciable amount of water.

The layer 9 is directly engaged with the under surface of the overlying sheet 6 and with the upper surface of the underlying sheet 7. The sheets and the layer are coupled together, a line of stitching 10 passing therethrough near the edges thereof and co-extensive with the perimeter of the pad.

The underlying sheet 7 may be processed to make it waterproof if desired. It would be necessary to have the underlying sheet 7 waterproof if the layer 9, for economical or structural reasons, should be made very thin.

To render it waterproof or liquid proof the underlying sheet 7, may be impregnated or coated with paraffine, oils, shellac, varnish, rubber or the like.

In the form of the invention shown in Figure 3 of the drawing, the overlying sheet 11 and the underlying sheet 12 are similar to sheets 6 and 7 of the above described form of the invention except that they are formed of woven reticulated materials such as wool, cotton or the like. The absorbent layer 13 is similar in all respects to the absorbent layer 9. The sheets 11 and 12 and layer 13 are

coupled together by two lines of stitching 14, 15, the outer line 14 continuous and co-extensive with the perimeter of the pad and located near the edge thereof and the inner line of 5 stitching being concentrically spaced therefrom.

In the form of the invention shown in Figures 4 and 5, the underlying sheet 16 is formed of paper that may be liquid or water-proofed like sheet 7 in the form disclosed in Figures 1 and 2 of the drawing. The overlying sheet 17 is illustrated as being formed of paper, but it is within the contemplation of the invention to form the same of fabric 15 as is shown in Figure 3 of the drawing.

The sheet 17 is imperforate but porous and provided with means co-extensive with and spaced from the edges thereof for attaching the pad to the bottoms of liquid containers 20 and articles of tableware. The particular means shown is an upstanding, integral crimp 18 formed in the body of the sheet to provide a rim about and spaced inwardly from the edge of the pad. Since the crimp 25 is formed of the body of the sheet 17 it will be somewhat flexible so that a frictional grip on the bottom of a glass, pitcher or other article of tableware, may be provided for, for attaching the pad thereto.

30 To maintain the form and upright position of the crimp 18 and also to couple the sheets 16, 17 and the layer 19 together, there is provided a line of stitching 20 which is made at the base of the crimp 18 and at the outward 35 side thereof and passes completely through the sheets 16, 17 and the layer 19. The absorbent layer 19 is similar in all respects to the absorbent layers 9 and 13. In addition to the line of stitching 20, there is provided a 40 second line of continuous stitching 21 which passes through the pad like the stitching 20 and is inwardly spaced therefrom.

It is to be understood that by describing in detail herein any particular form, structure, or arrangement, it is not intended to limit the invention beyond the terms of the several claims, or the requirements of the prior art.

Having thus described our invention, what 50 we claim is:

1. A coaster pad comprising a pair of sheets disposed in spaced relation to each other, the overlying sheet being capable of passing liquid therethrough and the underlying sheet being liquid-proof, a layer of loose fibrous liquid absorbing material disposed between said sheets, the layer and sheets being coupled together to form a composite pad, said overlying sheet having an integral up- 55 standing ridge projecting from its upper surface inwardly of the edge thereof to closely receive and grip the bottom portion of a receptacle so that the receptacle is made to carry the coaster pad whenever the receptacle is lifted or otherwise moved.

2. A coaster pad comprising a pair of co-extensive sheets disposed in spaced relation to each other, the overlying sheet being capable of passing liquid therethrough and the underlying sheet being liquid-proof, a layer 70 of loose fibrous liquid absorbing material disposed between said sheets, the layer and sheets being coupled together to form a composite pad, said overlying sheet having an integral upstanding ridge inward of its edge 75 projecting from its upper surface to closely receive and grip the bottom portion of a receptacle so that the receptacle is made to carry the coaster pad whenever the receptacle is lifted or otherwise moved, said ridge being a fold in the material of the overlying sheet.

3. A pad of the type described comprising a pair of sheets disposed in spaced relation to each other, the overlying sheet being capable of passing fluid therethrough, and the underlying sheet being moisture proofed, a layer of loose fibrous liquid absorbing material disposed between said sheets, securing means extending through the layer and the 85 sheets for coupling them together to form a composite pad, a crimp near the edge of said overlying sheet constituting an integral upstanding ridge to closely receive and grip the bottom portion of a receptacle so that the receptacle is made to carry the coaster 90 pad whenever the receptacle is lifted or otherwise moved, said securing means being located immediately adjacent the ridge.

4. A pad of the type described comprising 100 a pair of sheets disposed in spaced relation to each other, the overlying sheet being capable of passing fluid therethrough, and the underlying sheet being moisture proofed, a layer of loose fibrous liquid absorbing material disposed between said sheets, securing means extending through the layer and the sheets for coupling them together to form a composite pad, a crimp near the edge of said 105 overlying sheet constituting an integral upstanding ridge to closely receive and grip the bottom portion of a receptacle so that the receptacle is made to carry the coaster pad whenever the receptacle is lifted or otherwise moved, said securing means being located immediately adjacent the ridge and outwardly 110 thereof.

In testimony whereof we affix our signatures.

HENRY G. VENABLE.
GEORGIA N. VENABLE.
